UNITED STATES PATENT OFFICE.

GEORGE W. KUENNETH, OF PATERSON, NEW JERSEY, ASSIGNEE, BY MESNE ASSIGNMENTS, TO JEANNETTE KUENNETH, OF PATERSON, NEW JERSEY.

TENSION-CONTROLLING MEANS FOR BEAMING MACHINES.

Application filed December 8, 1918. Serial No. 265,128.

To all whom it may concern:

Be it known that I, GEORGE W. KUENNETH, a citizen of the United States, residing at Paterson, in the county of Passaic and 5 State of New Jersey, have invented certain new and useful Improvements in Tension-Controlling Means for Beaming Machines, of which the following is a specification.

This invention relates to beaming machines, and its object is to provide means in such machines whereby to maintain at all times an equable tension and avoid undue strain on the warp; according to my invention it is possible to adjust the amount of 10 tension so that the strain on the warp will be precisely what the quality of material 15 can stand and should have and no more.

In the accompanying drawings,

Figure 1 is a side elevation of a beaming 20 machine, containing my improvements;

Figure 2 is a front elevation, the reel and the beam-supporting and driving means being omitted;

Figure 3 is a side elevation of the lever 25 structure for exerting pressure against one face of the warp;

Figure 4 is a sectional view on line 4—4 of Figure 3;

Figure 5 is a side elevation of the lever 30 structure which controls the brake;

Figure 6 is a plan view, partly in section, of the last-named lever structure and its bearing bracket, one arm of said lever structure appearing in section; and

Figure 7 is a sectional view on line 7—7, 35 Figure 5.

In a suitable frame generally designated by the character *a* is journaled the beam *b* having any suitable means, as *c*, to rotate it.

40 *d* is a brake consisting of the usual strap which at one end is attached to the frame and at the other end has connected thereto a lever structure to be described, the strap bearing in the usual manner against a brake-band *e* on the reel.

A lever structure *f* is fulcrumed at the beam end of the machine in a pair of uprights *g* upstanding from the sides of the frame. This lever structure consists of a 50 shaft *h* journaled in the uprights and suitably held against longitudinal movement therein, a pair of levers *i* secured on the shaft one near each end thereof and each having upwardly, downwardly, and rearwardly extending arms *i'*, *i''*, *i'''*, and a

roller *j* journaled in the arms *i'*. The roller *j* is arranged below a roller *k* which is journaled in the uprights. Roller *k* forms a guide for the warp *A*, which extends (between the reel and beam) in front of roller *k* and back of roller *j*. To facilitate thus establishing the warp under the control of the part of my mechanism now being described the rollers *j* and *k* are preferably 60 removably mounted, as shown. The free end of the arm *i'''* of each lever *i* is adapted to receive weights *l*.

A bell-crank lever structure *m* is fulcrumed in the bracket *n* secured to each side of the frame. This lever structure includes 70 a shaft *o* journaled in the bracket and a rearwardly projecting arm *p'* and an upwardly projecting arm *p''* secured to the shaft; there is also a crank *p'''* secured to the shaft to which the free end of the brake-strap *d* 75 is connected. The arm *p'* may carry the weights *q*.

Lever structures *f* and *m* are coupled together as follows: A long link *r* is pivoted at one end to the arm *i'* of the lever *i* of the lever structure *f* and at its free end it includes a suitable loop *s* whose slot *t* receives the arm *p''* of lever structure *m* on which it is supported by the clip *u* vertically 80 adjustably secured on said arm. The slot *t* of the loop allows certain lost-motion as 85 between the link and lever structure *m*. The link is rendered adjustable in effective length by a threaded connection *v* between the body 90 part and loop thereof.

A spiral spring *w* is secured to a stud *x* pivoted to the arm *i'''* of the near lever *i* of lever structure *f* and carries at its free end a loop *y* whose longitudinal slot receives a pin *z* on the adjoining upright *g*.

In view of the foregoing and with the warp *A* arranged to extend around the rollers *j*—*k* in the manner stated, it will be apparent that the lever structure *f* will absorb any undue strains which might otherwise be imposed on the warp, notably such as is incident to overcoming the resistance of the reel when the beam is started rotating. The link *r* is adjusted so that when (depending upon the amount of weight *l* imposed on lever structure *f*) lever *f* is caused by the tautening warp to approach a certain position the lost-motion afforded by slot *t* in the link *s* will be expended, in consequence of which lever structure *m* will be moved, re- 100 105 110

laxing the tension on the brake-strap d (which it normally holds set) and consequently reducing the braking resistance. Thus my invention not only contemplates means to absorb strains on the warp but means controlled thereby to vary the resistance of the reel to rotation. The beneficial result obtained may perhaps best be exemplified by reference to the starting-up phase of the operation: In ordinary warping machines the brake-pressure is fixed and as there is not only the inertia of the reel but the adhesion of the brake to be overcome the strain on the warp is one moment excessive and the next greatly reduced; by my invention these extremes of strains are entirely eliminated because the braking resistance fluctuates inversely to the tension.

When the power is cut off from the beam the relaxation of the warp A between the beam and reel is obviously taken up by the lever structure f , which keeps the tension the same as when the beaming operation is in progress. On stopping the rotation of the beam the weighted lever structure f will fall back, tending to cause a rotative gain of the reel on the beam, which is at once overcome by the brake d . The stopping of the reel too suddenly, with consequent possibility of straining the warp or breaking some of its threads, is at this time prevented by the cushioning device w which (though inactive up to this point, on account of slot z) now comes into action by the end of its slot z engaging pin y , so that said device resists weights l and eases the braking action. Incidentally, the cushioning device also eases the pressure movement of lever structure f .
In order to leave the machine standing (when not in operation) without lever structure f exerting pressure on the warp I provide a latch 2 (Figure 1) which serves to

lock the lever structure in inactive position; the lever structure may be shifted to this position by hand 3 attached to one end of its shaft h —Figure 2.

Having thus fully described my invention, what I claim as new and desire to secure by Letters Patent is:—

1. The combination, with the frame of a beaming machine, a reel and a beam therein, and a brake for the reel, of yielding means to exert pressure against one face of the warp between the reel and beam normally holding the brake set, and a cushioning control for said means operatively interposed between the same and the frame.

2. The combination, with the frame of a beaming machine, a reel and a beam journaled therein, an upstanding lever fulcrumed in the frame and adapted to rest against the warp between the reel and beam, a brake for the reel, another upstanding lever normally holding the brake set, and a power transmitting link pivoted to one lever and pivotally supported on and having a lost-motion connection with the other lever.

3. The combination, with the frame of a beaming machine and a reel and beam journaled therein, of yielding means to exert pressure against one face of the warp between the reel and beam, and elastic cushion means, connecting the yielding means with the frame, to resist the pressure movement of said yielding means.

4. The combination, with the frame of a beaming machine and a reel and beam journaled therein, of yielding means to exert pressure against one face of the warp between the reel and beam, and lost-motion elastic cushion means, connecting the yielding means with the frame, to resist the pressure movement of said yielding means.

In testimony whereof I affix my signature.

GEO. W. KUENNETH.
